UNITED STATES PATENT OFFICE

171,656

SHOE OR SIMILAR ARTICLE

Roy Maling, Brookline, Mass.

Application March 12, 1953, Serial No. 23,999

Term of patent 7 years

(Cl. D7—7)

To all whom it may concern:

Be it known that I, Roy Maling, a citizen of the United States, residing in Brookline, in the county of Norfolk and State of Massachusetts, have invented a new, original, and ornamental Design for a Shoe or Similar Article, of which the following is a specification, reference being had to the accompanying drawing, forming part thereof.

In the drawing:

Fig. 1 is a side elevation of a shoe showing my new design, both sides of the shoe being substantially the same;

Fig. 2 is a top plan view thereof; and

Fig. 3 is a rear elevation thereof.

I claim:

The ornamental design for a shoe or similar article, substantially as shown and described.

ROY MALING.
